R. A. HARRIS

LINGERIE CHAIN

Filed Dec. 14. 1927

Ray A. Harris,

INVENTOR

BY Victor J. Evans

ATTORNEY

P. J. Evans

WITNESS:

UNITED STATES PATENT OFFICE.

RAY A. HARRIS, OF NORTH WINDHAM, CONNECTICUT.

DESIGN FOR A LINGERIE CHAIN.

Application filed December 14, 1927. Serial No. 24,486. Term of patent 7 years.

To all whom it may concern:

Be it known that I, RAY A. HARRIS, a citizen of the United States of America, residing at North Windham, in the county of Windham and State of Connecticut, have invented a new, original, and ornamental Design for a Lingerie Chain, of which the following is a specification, reference being had to the accompanying drawings, forming a part thereof.

The figure is a perspective view of the article showing my new design.

I claim:

The ornamental design for a lingerie chain as shown.

RAY A. HARRIS.
